STUDIO COUCH

Elmer T. Wuest and Herbert A. Wuest, Cincinnati, Ohio, assignors to Adam Wuest, Inc., Cincinnati, Ohio, a corporation of Ohio

Application April 6, 1938, Serial No. 200,451

4 Claims. (Cl. 5—18)

The present invention relates to a studio couch, or what is known as a bed couch, which may be extended to furnish a bed or collapsed to furnish a couch or seat.

5 An object of the invention is to provide a couch of the character referred to, which includes a novel triple-purpose means to facilitate the extension of one couch section, to lend support to the other section, and to automatically 10 lock the section against accidental separation.

A further object of the invention is to accomplish the objective above mentioned, with the use of a simple, inexpensive, and effective means which requires no adjusting, servicing, or 15 replacement of parts throughout the life of the couch.

Another object of the invention is to dispense with highly mechanized construction in the accomplishment of the objectives stated, and to 20 eliminate the customary stooping and tugging heretofore necessarily resorted to in extending one couch section relative to the other.

These and other objects are attained by the means described herein and disclosed in the 25 accompanying drawing, in which:

Fig. 1 is an end view, part being broken away, showing a couch embodying the present invention.

30 Fig. 2 is a perspective view of a swing bar of the invention.

Fig. 3 is a perspective view showing a modified form of swing bar.

Fig. 4 is a front view of the couch, showing the normal position of the swing bar, this view 35 being on a reduced scale.

In the drawing, the character 5 indicates a stationary couch section which includes a support 9 for a mattress and other bed equipment, said section having attached thereto, as at 7, an upper 40 right inverted U-shaped back rest 8. The back rest may be of any suitable construction, and as shown it comprises merely a bent tube or pipe having upstanding portions 9 and 10 connected by a transverse section 12.

45 A movable couch section which comprises front, rear, and side frame members, indicated at 13, 14, 15 and 16 respectively, is adapted to normally cover the stationary couch section. The movable section, being provided with rolls or other guiding means 17, is shiftable to extended and retracted positions relative to the stationary section. The illustration of the drawing shows the movable section in the retracted or normal position.

50 By preference, the movable section includes a

pair of arm rests 18 at opposite ends of the couch, supported upon one or more standards 19. The arm rests, of course, are elevated above the couch sections and above the cushions ordinarily supported thereon, which cushions are not disclosed 5 herein.

Devices of the general character thus far described are well known in the art, however, the problem of extending the movable couch section without extraordinary effort has always been one 10 of concern to the manufacturers of convertible couches. In the past, it was necessary for the user to stoop and tug at the movable section, or to operate some unwieldy mechanical means in order to effect an extension of the couch sections. 15 In accordance with the present invention however there has been provided a more convenient, simple, and effective means for that purpose, details of which will be explained presently.

It should be noted that each side member of the 20 movable section carries a bracket or bearing means 20, preferably at a location substantially midway between the front and rear frame members 13 and 14. These brackets or bearings are adapted to pivotally support what will be referred 25 to herein as a triple-purpose swing bar, two forms of which are shown in Figs. 2 and 3. Each swing bar comprises a pair of bearing ends 21 formed, in the simplest manner, by turning outwardly the free ends of the parallel arms 22 and 23 which 30 constitute the swing bars. At the rear end of each arm, the bar is bent in such a manner as to provide a handle bar 24 which is elevated considerably above the pivotal mounting at the free ends of the parallel arms aforesaid. Figs. 2 and 35 3 illustrate two different ways of forming the handle bar. In accordance with Fig. 2, the arms 22 and 23 are bent upwardly substantially at right angles and in parallelism, as indicated at 25 and 26 to provide risers, the upper ends of which 40 risers are connected by means of the handle bar. In this form of swing bar, the handle part substantially spans the end frame members of the couch, as may readily be evidenced by reference to Fig. 4. By moving the swing bar to the broken line position 27 of Fig. 1, the user may grasp 45 the handle bar to conveniently extend the movable section, using the swing bar as a so-called draw bar. After the movable section has been fully extended, the swing bar may be dropped 50 downwardly to assume a position adjacent to the front frame member 13 of the movable couch section. In the embodiment shown, the pivoted arm portions would rest upon the upper edges 55 of the side frame members 15 and 16. It should

be noted that in the normal position of the swing bar, as illustrated in Fig. 1, the handle portion is disposed at an elevation above the movable couch section so as to be accessible when cushions are in position upon the couch.

As before stated the swing bar of this invention performs three distinct functions: firstly, it provides a draw bar to be grasped for extending the movable couch section, secondly, it furnishes a means of preventing accidental displacement of the movable section while the couch is in use as a seat, and thirdly, it provides an effective means for bracing the back rest which ordinarily has but a single point of support where connection is made to the stationary couch section, as at 7. The last two functions of the swing bar result from its cooperation with a simple attachment which may be referred to as a latch means 28 applied to one or both sides of the back rest at substantially the elevation of the handle bar 24. This latch means may be simply a length of strap metal attached to the back rest in any suitable manner, such as by means of screws or other fasteners 29, a portion of the strap being developed into an end hook 30 providing an open topped recess or pocket 31. In the Fig. 1 embodiment, the handle bar will naturally fall into the open topped pocket when the swing bar is moved to the normal position shown, provided that the movable couch section is fully retracted. The parallel arms 22 and 23 may rest upon the upper edges of the side frame members 15 and 16 when the handle bar portion of the swing bar rests within the pocket or recess of the latch element. With the parts in this position, it will be impossible for a person sitting on the couch, to lean against the back rest and thereby unintentionally shift the movable section forwardly. Moreover, a person resting his back against the back rest 12 may not place a great strain upon the back rest at the point of connection 7 thereof with the stationary couch section, as the hooked end of the latch element will engage the swing bar to furnish added support against rearward distortion or bending of the back rest. From the foregoing it should readily be understood that the swing bar of the invention effectively performs three separate functions, without the aid of expensive and complicated mechanism. The user, in seeking to extend the movable couch section is entirely unaware of the existence of the latch member 28 since it is unnecessary for him to release any catches or otherwise concern himself with preliminary acts preceding the actual withdrawal of the movable section. In other words, the latching and unlatching of the swing bar is entirely automatic.

Should the couch be equipped with the type of swing bar disclosed in Fig. 3, the mode of use would be unchanged, since a latch member essentially the same as that shown at 28 will be mounted in fixed relation to the back rest or any other location of the stationary couch section at which some point, such as A or B, of the swing bar may rest within the open topped pocket or recess of the latch member. The clamp member, in this instance, would necessarily be at a somewhat lower elevation than is indicated in Figs. 1 and 2, however, the functions thereof would be identical.

As indicated at 32 of Fig. 1, a protective board or plate may be extended across the ends of the movable section, and disposed in close proximity with the bracket 20 and the swing bar, in order

to preclude injury to any upholstering material that may be applied to the movable couch section at that location. Such a board or plate may be employed also in couches from which the upholstering material is omitted at the ends of the couch. The form of the protective part 32 may be varied to suit the various designs of couch ends.

At this point in the description it may be mentioned that the particular angular structure of the swing bar may be varied, with perhaps some loss of advantage, while retaining the fundamental purposes thereof, for example, with reference to Fig. 2, the portion 23 might be extended directly to the handle portion 24, instead of reaching the handle portion by way of the angularity between the parts 23 and 26, thereby omitting the risers completely. Such a construction, however, might be objected to from the standpoint of appearance, although it would be an operative construction. Also, with some loss of advantage, the risers could be omitted, and the handle portion 24 disposed across the arms 22 and 23 in the plane thereof. It is to be understood that such modifications and changes in structural details may be made, within the scope of the appended claims, without departing from the spirit of the invention.

What is claimed is:

1. In a couch of the character described, the combination which comprises: a stationary couch section including a back rest extending upwardly at the rear thereof, a movable section shiftable to extended and retracted positions relative to the stationary section, said movable section including front, rear and side frame members movable toward and from the back rest of the stationary section, a bearing on each side frame member intermediate the front and rear frame members, and a swing bar substantially spanning the side frame members, said swing bar comprising a pair of arms each having a free end pivoted in the side member bearings, risers extending upwardly from the arms, and a handle bar connecting said risers and disposed at an elevation above the movable couch section so as to be readily grasped, for moving the swing bar about its pivots and manually extending the movable section using the handle bar as a draw bar, and a latch element fixed relative to the back rest and having an open topped pocket to receive the swing bar and latch the couch sections against accidental relative movement.

2. In a couch of the character described, the combination which comprises: a stationary couch section including a back rest extending upwardly at the rear thereof, a movable section shiftable to extended and retracted positions relative to the stationary section, said movable section including front, rear and side frame members movable toward and from the back rest of the stationary section, a bearing on each side frame member intermediate the front and rear frame members, and a swing bar substantially spanning the side frame members, said swing bar comprising a pair of arms each having a free end pivoted in the side member bearings, with the arms normally disposed in substantial parallelism with the side frame members, risers extending upwardly from the arms to an elevation above the movable couch section, a handle bar connecting said risers at said elevation to provide ready access for actuation of the swing bar about its bearing mounts, and a latch means normally connecting the swing bar to the back rest for pre-

cluding accidental shifting of the couch sections from the collapsed relationship.

3. In a couch of the character described, the combination which comprises: a stationary couch section, and a movable section shiftable to extended and retracted positions relative to the stationary section, said movable section including front, rear, and side frame members, a bearing on each side frame member intermediate the front and rear frame members, and a swing bar substantially spanning the side frame members, said swing bar comprising a pair of arms each having a free end pivoted in the side member bearings for swinging movement from the region of the rear frame member toward the front frame member of the movable section, means including a handle bar connecting the arms and movable therewith to provide a hand grasp for pulling the movable section to the extended position, and holding means on the stationary couch section providing a socket for reception of the swing bar when it is pivotally moved to the region of the rear frame member of the movable section.

4. In a couch of the character described, the combination which comprises: a stationary couch

section including a back rest extending upwardly at the rear thereof, a movable section shiftable to extended and retracted positions relative to the stationary section, said movable section including front, rear, and side frame members, a bearing on each side frame member substantially midway between the front and rear frame members, and a swing bar substantially spanning the movable couch section from one side member to the other, said swing bar comprising a pair of arms pivoted to the side member bearings and extending rearwardly along the side frame members to a location adjacent to the back rest of the stationary frame member, risers extending upwardly from the arms in close parallelism with portions of the back rest, and a handle bar connecting said risers at an elevation above the movable section of the couch, said handle bar swinging with the arms about their pivots to a position in advance of the front frame member of the movable couch section, and a socket on the back rest providing a restraining latch for the swing bar.
